UNITED STATES PATENT OFFICE

JOHN EDWARD ERGANBRACK, OF CHICAGO, ILLINOIS

CASING AND COIL ASSEMBLY FOR HEAT TRANSFER DEVICES

Application filed November 8, 1929. Serial No. 405,588.

My present invention has relation to the provision of an assembly of casings and coils in heat transfer devices. As will hereafter be seen, the variety of heat transfer devices in connection with which I have illustrated my invention are designed for the transfer of the heat of boiler water to service water employed for domestic, manufacturing or other purposes. In the class of heat transfer devices in connection with which I have illustrated the application of my invention there is provided a casing connected to the boiler in such a manner as to secure a thermal or gravity circulation of the boiler water through the casing and in the casing is installed a coil, for the absorption of heat from the boiler water, through which coil at least a portion of the service water supply is caused to pass. The cooling of the boiler water in the casing through the giving up of its heat to the coil is conducive to sedimentation of certain varieties of materials usually, or not infrequently, present in water supplies. While, on the other hand, the heating of the service water in the coil tends to cause a precipitation therein of elements almost always present in water supply in greater or less quantities which give to the water a character described as "hardness". The sedimentation and precipitation, heretofore noted, requires the cleaning from time to time of both the casing and the coil and to permit and facilitate a thorough cleaning it is highly desirable to design the casing and connect the same with the coil in such a manner as to permit of the easy disassembling and assembling of these parts. The provision of such a connection is the object of my invention.

I have attained the foregoing object by means of the instrumentalities illustrated in the accompanying drawings, in which—

Fig. 1 is a schematic illustration of a typical boiler, heat transfer device and service hot water storage tank with which my invention is advantageously employed;

Fig. 2 is a vertical central section through a casing and coil assembly embodying my invention;

Fig. 3 is a fragmental plan of the structure

shown in Fig. 2, a portion thereof being shown in section;

Fig. 4 is an end view of the coil member of the connection;

Fig. 5 is a central vertical section similar to Fig. 3 showing a modified form of casing and coil assembly;

Fig. 6 is a view of the inner end of the holding member of the connection;

Fig. 7 is a vertical central section of a still further modified casing and coil assembly; and

Fig. 8 is an end view looking towards the coil of the holding member of the connection.

Similar reference characters refer to similar parts throughout the respective views.

In Fig. 1 I have illustrated a typical form of boiler 10, either of the hot water or steam type, to which is connected by an upper feed pipe 11 and a lower return pipe 12, a heat transfer casing 13. The heat transfer casing 13 shown is generally cylindrical with the lower portion or bottom 14 integral and having a flange 15 at the top. The flange 15 is perforated at intervals 16 (as indicated in Fig. 3) for the passage of bolts for securing to the casing 13 the cover or closure 17. The integral bottom 14 of the casing is provided with a central embossment 18 which is bored and tapped for assembly with the return 12. The arrangement thus far described secures a thermal or gravity circulation of the boiler water through the casing 13.

At the top and bottom there is provided on one side of the casing hollow embossments 19 which communicate with the interior of the casing and which are formed in one of the manners hereinafter described for securing a heat transfer coil within the casing and assembling the coil with a hot water service supply.

All of the constructions hereinafter described employ a modification of what is known as a railroad joint or connection in which the meeting surfaces of the joint have a ground fit and at least one of which surfaces is partially cylindrical. A typical railroad joint is not adapted to the situation hereinafter described as the joints I employ must support the heat transfer coil as well as estab-

lishing connection between the coil and the casing, and I have supplemented the railroad joint in each of its applications herein shown by the addition of flanges which serve to support the heat transfer coil without bringing dislocating strains upon the ground or ceiling surfaces.

In Fig. 2 the hollow embossment 19 is bored laterally at 20 opposite the opening 21 which 10 provides communication between the embossment 19 and the interior of the casing 13. Upon the casing side the opening 21 is flared to provide the inclined surface 22 which is ground to form one seat of the connection. 15 About the interior edge of the inclined surface 22 is an interior, annular development 23.

Fittings 24 are brazed or otherwise secured to the ends of the heat transfer coil 25. The 20 end of the fitting 24 is provided with a ground somewhat spherical surface 26 which co-operates with the inclined surface 22 and back of the surface 26 the fitting 24 is provided with a shoulder 27 co-operating with the annular development 23 to support the weight of the heat transfer coil in the casing. The fitting 24 is provided with a spider 28, the center whereof is bored and tapped to receive the bolt 29.

30 The lateral opening 20 in the hollow embossment 19 has the outer portion thereof enlarged to provide an inclined or beveled surface 30, which is ground, and the inner portion of the head of the bolt 29 is provided 35 with a ground somewhat spherical surface 31 which co-operates with the inclined surface 30. The bolt 29 thus provided operates to draw and retain the fitting 24 in position and at the same time to close and seal the bore 20. 40 The hollow embossment 19 is bored and tapped from the top, as at 32, to receive the threaded pipe 33 constituting a connection between the coil and the hot water service system. The bottom hollow embossment 19 45 is precisely the same as heretofore described except that the bored and tapped hole 32 enters at the bottom instead of the top.

The construction shown in Figs. 5 and 6 differs from that shown in Figs. 2 to 4 inclusive in the omission of the spider 28 from the fitting 24 and for holding the fitting 24 in position the end of the fitting 24 is interiorly tapped, as at 34, which co-operates with a form of bolt, the stem whereof is expanded to form what might be called a conical or pyramidal spider 35, the inner or larger end whereof is threaded, as at 36, to co-operate with the threads 34 of the fitting 24. In this case the opening 20a has to be considerably 55 larger than the opening 20 to permit of the passage of the expanded bolt or spider but the exterior ceiling surfaces except being 60 larger correspond part for part with those shown in Fig. 2 as heretofore described.

65 The modification shown in Figs. 7 and 8

differs from those heretofore described principally in a longitudinal shortening of the holding element. In this last modification the spider is also omitted and the fitting 24 is provided with interior threads 34a. In this latter case, however, I provide, in connection with the inwardly facing oblique ground surface 22 an outwardly facing oblique ground surface 37. In this latter case the bolt 29 and the bolt with the spider development 35 is replaced by nipple 38, the outer end of which is enlarged and provided with an exterior ground surface 39 co-operating with the ground surface 37. Interior radial dogs 40 are provided in the enlarged end of the nipple 38 to receive a tool for screwing the nipple into position. In this case the lateral opening 20b through which the nipple is introduced is internally threaded to receive the ordinary threaded plug 41. In each embodiment of my invention I secure a connection between the heat transfer coil and the casing in which it is installed which may be easily assembled and disassembled and which has the efficacies and advantages of the ordinary railroad joint, while at the same time it provides support for the heat transfer coil which eliminates strain upon the ceiling connection between the coil and the casing.

Having described my invention what I claim is new and desire to secure by Letters Patent is:—

1. A casing and coil assembly in heat transfer devices comprising a casing provided with a pair of spaced hollow embossments having communication with the compartment within the casing, the casing side of the openings providing such communication being provided with a ground seat surrounded by an annular shoulder, a coil and fittings for the ends thereof, said batten provided with interior spider brackets and ground seats co-operating with the seats in said casing, and provided with cylindric portions entering said annular shoulders, said hollow embossments being bored and provided with ground seats opposite their points of communication with said casing, and bolts the heads whereof have seats co-operating with said last mentioned seats extending into co-operation with said spiders.

2. In a casing and coil assembly for heat transfer devices, a casing having a main and auxiliary entrance and discharge chambers, opposing ports in said auxiliary chambers leading from the main chamber in the casing and to the exterior of the auxiliary chamber, opposing seats adjacent said respective ports, a coil fitting co-operating with the inner of said seats, and a holding member 120 seating on the other of said seats and extending into engagement with said coil fitting.

3. In a casing and coil assembly, a casing having a main and an auxiliary chamber with a port affording communication therebe- 130

tween, seats opposing related to said port, a coil fitting co-operating with one of said seats, and a holding member co-operating with the other of said seats and extending 5 into engagement with said coil fitting.

4. In a casing and coil assembly, a casing having a port, an inwardly facing seat with an annular shoulder upon one side of said port, a seat disposed opposite said first mentioned seat, a coil fitting having a cylindrical portion and a seat co-operating with said seat and shoulder and a holding member co-operating with said opposing seat and extending into engagement with said coil fitting.

15 5. In a casing and coil assembly, a casing having a port, an inwardly facing seat upon one side of said port, a seat disposed opposite said first mentioned seat, a coil fitting having a seat co-operating with said first mentioned 20 seat and a holding member co-operating with said opposing seat and extending into engagement with said coil fitting.

JOHN EDWARD ERCANBRACK.
